UNITED STATES PATENT OFFICE

WILLIAM FORSTNER, OF IRVINGTON, NEW JERSEY, ASSIGNEE TO FORSTNER CHAIN CORPORATION, OF IRVINGTON, NEW JERSEY, A CORPORATION OF NEW JERSEY

CHAIN

Application filed April 14, 1925. Serial No. 22,986.

This invention relates to an improved construction of ornamental chain for personal wear, and has for its object to provide simple and effective means for applying ornamentation to the links of a chain.

5 A further object of this invention is the provision of a chain having a plurality of elongated loop-like links and the provision of an ornamental block or member grooved longitudinally and adapted to be mounted in each loop link between the arms thereof, the arms being forced together to closely embrace the ornamental member and bind it in position, these loop links being connected together 15 by connector links.

20 A further object of the invention is to provide further ornamentation by twisting the ornamental block and the arms embracing the same, which twisting action serves to more closely bind or force the arms into the grooves of the block.

25 A still further object of the invention consists in the connecting of these elongated links by connector links of S-shape. These connector links being of a character to strongly resist an opening strain thereon so as to firmly secure the long links together without the necessity of soldering the ends of the S-link.

30 With these and other objects in view, the invention consists of certain novel features of construction, as will be more fully described, and particularly pointed out in the appended claims.

35 In the accompanying drawings:

Figure 1 is a side elevation illustrating a short length of chain constructed of elongated links of different characters connected by S-links.

40 Figure 2 is a perspective view showing one of the grooved block ornaments as removed from its elongated loop link.

Figure 3 is a perspective view showing one 45 of the elongated loop-links.

Figure 4 is a perspective view showing one of the elongated loop-links with its arms embracing an ornamental block mounted therein.

50 Figure 5 shows the block as mounted be-

tween the arms of the loop-link, both being twisted a one-half turn.

Figure 6 is a side elevation of the S-shaped link with its ends open.

Figure 7 is a side elevation showing the 55 S-link with its ends closed to connect adjacent loop-links together.

It is found in the construction of ornamental chains for personal wear, of advantage to form a variety of styles of ornamentation on 60 the links thereof; also it is found of advantage to form certain of the links separately so that they may be finished in groups and ornamented or treated to receive different colors

such as green gold, red gold, yellow gold and 65 white gold, and after these groups have been so treated and colored, to be able to connect the differently colored links in different ways to produce a variety of different artistic effects, and to accomplish this in a simple and 70 effective way, I have formed a set of elongated loop-links which may be treated in a certain way, and I have provided a set of ornamentations for these different loop-links which, in themselves, may be treated in a dif-

ferent way from that of the loops and subsequently inserted by being snapped into position between the arms of the loop links and subsequently embraced by the arms of the 75 loop-links without the use of solder. In other 80 instances, I may, after inserting the ornamental link between the arms of the loop-link, twist this loop-link with its filler block to present another form of ornamentation, and

it is found of advantage to connect these 85 differently-treated links together by a connector link which is so formed as not to require its ends to be soldered, and to accomplish this I have preferably formed this connector link in an S-shape, the wire of the S being hard-

ened or made very stiff by the inherent qualities of the wire so as to tenaciously resist an 90 opening action and so be as strong as the other loops of the link even though its joints remain unsoldered; and the following is a 95 detailed description of the present embodiment of my invention by which these advantageous results may be obtained:—

With reference to the drawings, 10 designates the elongated loop-link which may be 100

made of any desired wire and of any desired size and dipped or treated to obtain any desired coloring effect.

In order to provide a simple and effective ornamentation for this link, I have formed a block member 11 which is preferably of a length less than that of the link.

This block is preferably provided with longitudinally-disposed grooves 12 on its opposite edges and is adapted to be snapped between the arms 13 of this long loop, and these arms are then pressed down into the grooves 12 to secure and bind the ornamentation therein. As the length of this block is less than that of the link a space 14 is left at opposite ends thereof providing eyes or spaces through which the connecting link 15, presently described, is passed. These blocks 11 may be finished or treated independently of the link and dipped or colored differently from that of the loop, if desired, and when snapped into position be retained therein without the use of solder, thereby preventing discoloration of the parts which would be the case if soldering heat should be applied thereto.

In some instances, after this block has been positioned in the loop, I twist this loop and block to an angle of about 160° , if desired, as best illustrated in Figure 5, to provide further ornamentation for the link.

In connecting these elongated loops together, I preferably employ an S-shaped link 15, the wire of which may be of any shape in cross section but which is preferably formed of very hard and stiff material and has preferably as great or greater resistance than any of the other links of the chain so that when its ends 17 are closed upon the shank 18 thereof its great resistance to a separating strain will prevent it from opening and so be as strong as any of the other soldered or integral links of the chain, it being understood that the shank portion of the S-shaped portion being of a continuous wire serves to greatly resist an opening action on the link as this continuous member receives one-half of the opening strain which may be applied to both of the eyes thereof, one quarter being taken by one loop, and the other quarter by the opposite loops.

It is also found of advantage to connect the ends of this wire so as to lie squarely against opposite sides of the shank thereof so as to reduce the joint opening to the minimum.

My improved form of chain is very inexpensive to construct as it may be assembled automatically by machinery. This chain also lends itself to presenting a great variety of colors and ornamentation and may be entirely assembled by machinery and without the use of solder.

The foregoing description is directed solely towards the construction illustrated, but I desire it to be understood that I reserve the

privilege of resorting to all the mechanical changes to which the device is susceptible, the invention being defined and limited only by the terms of the appended claim.

I claim:

A chain having elongated loop-links with bendable side arms, and ornamental metallic members of a length slightly less but of a width greater than that of the link and of an approximately rectangular cross-section but having two diagonally opposite corners cut away to provide longitudinally extending grooves, the angular relation of the remaining corners of the cross-section of the members causing each member to enter and snap between the side arms of a loop link and lie therein throughout its length, said arms being bent to lie in the grooves, and links extending through the spaces between the ends of said members and the loop links to connect said loop links together.

In testimony whereof I affix my signature.

WILLIAM FORSTNER.
